UNITED STATES PATENT OFFICE.

ALLEN C. STALEY, OF LA FAYETTE, INDIANA.

STEAM AUTOMOTIVE-VEHICLE BOILER.

Application filed March 8, 1922. Serial No. 541,974.

This invention relates to steam boilers or generators particularly applied to steam driven vehicles where weight, accessibility, and ease of repair in combination with a 5 self contained compact unit of high power output and small weight are necessary qualifications.

The design described herewith possesses these characteristics to a marked degree, the 10 particular features being brought out in the following.

In the drawings I illustrate various improved structures which embody my invention, the object of my invention appearing 15 hereinafter.

Figure 1 is a vertical section of the device of my invention,

Figure 2, a section through the headers shown in Figure 1,

20 Figure 3, a section illustrating improved means for securing the end of a steam pipe to a header, and

Figure 4, a similar view of a modified form.

25 In the drawings reference character 1 represents a combustion chamber, which in this case is shown for use with liquid fuel fire, the same entering the chamber 1 from the burner nozzle 10. It is understood, however, 30 that this burner or combustion chamber may be of any desired design, the one shown being merely illustrative of a type suitable for use with this boiler.

As mentioned above, the fuel and air required for combustion enter the combustion chamber 1 where they are retained until combustion is completed, when the products resulting from the combustion rise upward through the opening 9 in the top of the combustion chamber, thence passing over and giving up their heat to the superheater coils 6, steam tubes 11, and water heater or economizer tubes 2. The temperature of the gases having been reduced to the desired minimum 45 they pass out by way of the flue under the top cover 8.

The entering water is supplied to the boiler through pipe 15 under pressure by suitable pumps or other devices not shown. 50 It first comes into contact with the heated products of combustion in passing through the economizer coils 2, where the contra-flow principle of bringing the coldest water in contact with the coldest gases is fully utilized. This ensures the maximum tempera-

ture difference between the water and gases and thereby secures the maximum heat absorption per unit of coil surface.

After leaving the economizer the water enters the boiler header 3, by means of the 60 feed water pipe 4 in such a manner as to go to the bottom of the header first. This ensures that any scale or sediment that may be in the water will tend to be deposited at this point which is out of the direct heat of 65 the fire. This provides against the formation of a hard deposit, and the accumulation of sediment is located in a position to be readily removed by opening a blow-off valve, 14.

70 From here the water rises by natural circulation until it reaches the entrance 16 to the steam loops or tubes 11 where it meets the direct blast of the fire and consequently circulates rapidly in these tubes owing to the 75 rapid formation of steam bubbles and the high rate of heat absorption. The steam and water pass out of the tubes 11 into the headers again the water falling by gravity and so entering into circulation once more while 80 the steam rises to the upper part of the headers where it is drawn off as required.

The pitch of the steam tubes is such as to prevent any tendency to reverse the circulation even under extremely heavy steaming, 85 and the water level being maintained automatically below the steam tube outlets into the main headers, there is no retardation of the circulation which is designed to attain exceedingly high velocities. This causes a 90 scrubbing action on the tubes preventing scale formation and ensuring high rates of heat transmission per unit of tube surface.

This principle of so called, accelerated circulation, has been very successful in 95 marine installations in general and torpedo boats and destroyers in particular where high steaming capacities are demanded from relatively small units.

100 In the large area of the steam headers above the water level, the velocities are reduced to a low figure permitting the entrained water to fall back into the water zone to be recirculated through the steam tubes, while the steam is passing slowly upward frees itself from the entrained moisture and arrives at the outlet pipe 5 in a 105 dry or slightly superheated condition.

110 From here, the steam is led through the pipe 7, in which may be inserted the throttle

valve if desired, to the superheater coils 6 where it is given its final heating preliminary to passing to the engine.

The superheater is shown in the drawing 5 located immediately over the firebox where it receives the full force of the fire. This is done with the intention of securing the largest possible heating effect from the 10 smallest amount of tubing, which is accomplished by using this location. In order to obtain longer service from the superheater, other locations may be used such as immediately above the steam tubes and just below the economizer coils. This will require 15 of course somewhat more tube surface to secure the same superheating effect as the gases have been cooled down in passing over the steam tubes, but the life of the superheater will be greatly lengthened thereby and if weight is not of paramount importance more satisfactory results will be 20 secured.

The apparatus and operation thereof 25 heretofore described is not necessarily new nor novel, only skill and good judgment being required in locating and proportioning the elements entering into the design to secure a rapid steaming unit, well arranged for large capacity with a minimum of 30 weight and heating surface, the whole being developed into a compact and neatly arranged construction. The headers act as a container which may be readily insulated so as to avoid undue radiation losses, as the 35 insulation is not subjected to the direct heat of the hot gases so that ordinary materials readily suffice for this purpose.

It is a well known fact that it is extremely 40 desirable that steam be raised on a cold boiler in as short a time as possible, as delays in starting are not conducive to satisfactory operation. In this design with an electrically ignited fire using liquid fuel, this is readily accomplished in less than a 45 minute, as the water in the steam tubes, being of comparatively small volume, is rapidly heated and converted into sufficient steam to fill the space in the headers, without requiring the heating of the entire volume of 50 water in the system to steam temperature, as in the usual type of fire tube or pot boiler. In fact, steam can be raised to operating pressure with the water in the lower part of the headers sufficiently cool to be 55 comfortable to the touch. This valuable characteristic of this design permits rapid starting from cold and getting under way. After the vehicle is under way the balance 60 of the water is gradually heated up to working temperature ready for quick conversion into steam, and the thermal storage of this volume of water is available for conversion into mechanical energy by a reduction of pressure due to a heavy pull or sudden demand.

Thus this design combines at one and the same time the initially quick steaming from cold characteristic of the continuous flow or semi-flash type of generator and the stored power or ability to deliver steam in 70 excess of its normal steaming rate peculiar to the pot type of boiler.

It is also a well known fact that in boilers as usually constructed without economizers, 75 that 60% to 70% of the heat abstracted from the products of combustion and applied to the generation of steam occurs in the first 20% of the boiler surface swept over by the gases, while the remaining 30 to 40 per cent of heat requires the action of the 80 80% of boiler surface to absorb this relatively small amount of heat. In other words the first 20% of tube surface is about eight times as effective as the remaining 85 80% of the boiler as a steam producing apparatus, based on weight and surface of tubing required.

This is due to the fact that the water in all the tubing remains at steam temperature 90 while the gases become cooler and cooler as they approach the flue. This cooling reduces the temperature difference between water and gases and as a result the heat interchange per unit of surface swept over by the gases. When using an economizer the temperature 95 of water is usually much less than the steam temperature so that this becomes a much more effective instrument for abstracting heat from the partially cooled gases.

In the design proposed these principles 100 were taken into account and the steam tubes represent the 20% (percent) of surface as found in an ordinary boiler with the tube pitch and arrangement conducive to rapid water circulation and as a result they are 105 very effective as heat absorbers. The balance of the boiler is omitted due to its inefficiency and replaced by economizer tubing, a much more effective heat absorbing medium. This provides a unit that is not 110 stressed thermally beyond the limits of standard practice yet owing to the use of only those portions that are efficient as heat absorbers, the size and weight is greatly reduced below that required by a standard design 115 for the same steaming capacity.

With this arrangement the headers and economizer tubing should last indefinitely, the only portions requiring replacing being the steam and superheating tubing after a 120 long period of operation. This may be readily and cheaply done by disconnecting a few pipe joints and swinging the headers back so as to remove the steam tubes. By a system of annual inspection and replacement 125 of any steam tubes that may show signs of deterioration there are slight chances of having tube failures while on the road, yet in case such inspections are neglected and trouble results, it is very desirable to be able 130

to make a roadside repair job and get home on your own power. This is made possible by the method of attaching the steam tubes to the headers, the construction used being shown in Figures 3 and 4. It is noted that each tube 11 makes a tight joint with the header 3 to which it is connected, each end of the tube being welded or brazed to a nipple 18 of special shape which may be a forging that carries a tapered or beveled shoulder 19 resting against a seat 20 on the header. An extension of this nipple passes through the opposite wall of the header and is threaded at 21 so that shoulder 19 can be drawn up into fluid tight relation with the seat 20 by means of the special nut which bears against a beveled washer 22 adapted to be forced against a seat at 23 by tightening the nut. This forging is hollow for the passage of water and steam. In a modified (and preferred) form of the invention, as shown in Fig. 4, the forging 24 is provided with an internal seat formed in the screw plug 25. A valve 26 has a stem 27 protruding through the nut 28, and by means of such valve the flow of water may be cut off in any tube as desired.

By this arrangement in case of failure the faulty tube is quickly and easily cut off from the system and the plant operated as usual until such time as it may be convenient to make a renewal of the defective part.

It is also desired to call particular attention to the header construction and point out the differences and advantages over the usual methods employed. It is common practice in many constructions to weld the steam tubes to the vertical headers and have the headers interconnected by a number of pipes and joints. This is a costly and clumsy construction, hard to insulate, and difficult to align in assembling. These connections are sources of possible leakage owing to the strains set up by the distortion of the boiler due to road shocks and irregularities as well as by temperature strains. Furthermore it is necessary that there be a perfectly free circulation of water and steam between each header or section, in default of which differences in pressure will prevent maintaining the same water level in each section and burned tubes will result owing to insufficient water. For these reasons the unit header construction was chosen see Fig. 2 in which

all connections are made within the headers themselves and these are of ample area ensuring free flow of water and steam to each section ensuring an absolutely uniform water level through the boiler at all times.

In view of the fact that this boiler is designed to operate at high pressures such as 600 lbs. per sq. in. and upwards the usual header construction of stayed surfaces would be unsatisfactory from both a cost and weight viewpoint. It is to be noted, therefore, that the following construction is used.

All the headers are composed of a number of rectangular vertical seamless steel tubes open at top and bottom and of uniform length. The adjacent side walls are then cut away at the ends in such a manner that when placed side by side, the openings 29 so formed coincide. The edges 30 are then welded together making a steam and water tight joint and also securing the tubes tightly together in one unit. The ends which are still open are then closed by suitable plates or closing means also welded in place and after the required number of tubes are fastened together in this manner the header is complete after holes are drilled and reamed for the steam tubes and connections.

This makes an exceedingly light and sturdy construction capable of standing high pressures with safety.

I claim:

In a steam generator of the water level type, a fire-box, a series of tubular headers at each side of the fire box, each series of headers being interconnected and contacting to form a water wall, steam pipes above the fire-box each detachably secured at its ends to a header with one end above water level and the other below water level, an economizer above the steam pipes and within the space enclosed by said water wall, a superheater comprising a horizontal coil below said steam pipes, a passage leading from the bottom of the economizer to the lower end of the header below the fire-box, a blow-off valve adjacent the lower end of said pipe, and a passage leading from the upper ends of the headers to the superheater, substantially as set forth.

In testimony whereof I have hereunto set my hand.

ALLEN C. STALEY.
